UNITED STATES PATENT OFFICE.

CHARLES HOWARD AND JAMES J. KIRK, OF CHICAGO, ILLINOIS.

BOWL AND SHADE SUPPORT.

Application filed June 9, 1923. Serial No. 644,431.

To all whom it may concern:

Be it known that we, CHARLES HOWARD and JAMES J. KIRK, citizens of the United States, and residents of the city of Chicago, 5 in the county of Cook and State of Illinois, have invented certain new and useful Improvements in a Bowl and Shade Support; and we do hereby declare that the following is a full, clear, and exact description of the 10 same, reference being had to the accompanying drawings, and to the numerals of reference marked thereon, which form a part of this specification.

This invention relates to a shade or bowl 15 support for lamps and comprises a depending hood member having a cylindrical base, into which the upper neck of the shade or bowl is adapted to fit in combination with novel adjustable means for engaging the 20 shade or bowl and securing it to said support.

The invention comprises the novel mechanism and combination hereinafter described and more particularly pointed out and defined in the appended claims.

In the accompanying drawings which illustrate a preferred embodiment of this invention and in which similar reference numerals refer to similar features in the different views.

Fig. 1 is an elevational view of the shade or bowl support with a shade attached thereto.

Fig. 2 is an enlarged fragmentary vertical 35 sectional view of the same.

Fig. 3 is an enlarged horizontal section through the base of the shade support.

Fig. 4 is an enlarged section upon the line 4-4 of Fig. 2.

Fig. 5 is an enlarged view taken upon the 40 line 5-5 of Fig. 3.

Fig. 6 is a view taken upon the line 6-6 of Fig. 3.

In referring to the drawings, the reference 45 numeral 1 represents the shade support having a shade 2 attached thereto. The support preferably consists of a metal hood having a reduced upper portion provided with an aperture 3, whereby the same may be 50 readily suspended, and a cylindrical base 4 into which the attaching neck of the shade or bowl is adapted to fit.

Shade or bowl supporting means extends 55 circumferentially of the interior of the base and comprises a flexible portion adapted to

be expanded for receiving the neck of the shade or bowl and contracted for gripping or securing the shade or bowl to the support, and means are provided for varying the degree of flexure of the flexible portion for 60 fitting different sizes of shades and for retaining the same in operative or inoperative position.

In the illustrated embodiment of this invention the shade or bowl supporting means 65 comprises a member 5 secured circumferentially of the interior of the base and spaced a suitable distance from the wall thereof, and a flexible circumferential member 6 secured at its inner end and free at its outer 70 end, and adapted to be contracted or expanded. In the present instance, the members 5 and 6 constitute portions of a metal band rigidly secured at one end to the base by means of a rivet 7 and secured at an intermediate point by a rivet 8, the portion between the rivets being offset from the interior of the wall of the base and constituting the member 5. A third rivet 9 spaced a short distance from the rivet 8 marks the 80 beginning of the flexible member 6 which lies substantially opposite the offset portion or member 5. The forward end of the flexible member 6 which lies spaced substantially a quadrant from the rivet 7, has an 85 oscillatable member 10 in the form of a screw, pivoted thereto, which extends through a suitable slot in the wall of the cylindrical base and through a slot 11 in a keeper 12 secured to the outer surface of the 90 base. An adjustable nut 13 is positioned upon the screw 10, the outer end of the nut is reduced and in the form of a tenon that slidingly fits into the slot in the keeper 12, and the shoulders at the bottom of the tenon 95 are rounded or bevelled as shown in Fig. 3, the outer end of the screw is provided with a rounded head, which, in connection with the beveled shoulders of the tenon, forms a guide that operates in the slot 11. The 100 nut 13 may be adjusted to vary the contraction of the flexible member so as to clamp different sizes of shades or bowls.

A resilient or spring latching member 14 is attached to the screw 10. This latching member consists of a spring wire having a pair of parallel arms: intermediate the upper ends of the arms the wire is coiled around the screw. The lower or free ends of the arms are bent inwardly and looped 110

around the screw so that the arms may be pressed together. These resilient arms are adapted to slide in the guide-way of the keeper 12 and at one end of said guide-way there are a pair of oppositely-extending lateral notches 15 into which the arms 14 will snap when the screw lever 10 is swung into that end of the slot, which is the operative position thereof.

10 When the screw member 10 is swung into the dotted line position shown in Fig. 3, the flexible member 6 will expand so as to be closely against the interior surface of the support, allowing the upper neck of the shade or bowl to be inserted as shown in Fig. 2. Then by oscillating the screw or snapping it back into the full line position shown in Fig. 3, the flexible member 6 will be contracted or flexed inwardly to embrace the neck of the shade or bowl as shown in Fig. 2, which will be suspended from the members 5 and 6. When the screw 10 reaches its operative position, the resilient arms 14 will snap into the notches 15 and lock the screw in such position. The arms 14 can, however, be pressed together to release the screw for swinging it in the opposite direction. If the shade or bowl should not be sufficiently tightly 30 clamped between the circumferential supports 5 and 6, the nut 13 may be properly adjusted to produce a greater contraction of the flexible member 6.

It will be appreciated that a shade or 35 bowl can be readily and quickly applied and removed from the support, and that the shade or bowl retaining means can be adjusted to properly secure the shade or bowl and that the operation is quickly and 40 easily effected by simply snapping the screw backwards and forwardly.

We are aware that numerous details of construction may be varied through a wide range without departing from the principles of this invention and we therefore 45 do not purpose limiting the patent granted hereon otherwise than necessitated by the prior art.

We claim as our invention:

1. A shade holder comprising a member having a cylindrical base, a band secured interiorly of said base at intermediate points, said band being inwardly offset between said points, and having a free flexible portion beyond one of said points, said holder having a slot adjacent the free end of said flexible portion, a slotted keeper provided with notches secured to said holder in registry with said slot, an oscillative member secured to the free end of said flexible portion and extending through said keeper, and expansible and contractible means on said operating member adapted for engaging said notches. 50

2. A shade holder having a cylindrical base provided with a slot, a band secured interiorly of the base and having a free flexible portion extending adjacent said slot, a slotted keeper having opposed notches and secured upon said base over said slot, 55 an oscillating member secured to the free end of said band and extending through said slot and keeper, and resilient latching means on said operating member adapted for engagement with said notches. 60

3. A shade holder comprising a member having a cylindrical base, a band secured interiorly of said base with portions spaced from the wall thereof; one end of said band being freely movable, an oscillatable member secured to the free end of said band, a contractile and expansible latching means on said oscillatable member, said holder having a slot, a keeper on said holder having a slot, and lateral notches, said oscillatable member extending through said slots with the latching means adapted for locking engagement with said notches. 70 75 80

In testimony whereof we have hereunto subscribed our names in the presence of two 90 subscribing witnesses.

CHARLES HOWARD.

JAMES J. KIRK.
